CLAIM

The ornamental design for a medical apparatus for imaging, as shown and described.

DESCRIPTION

FIG. 1 is a front elevational view of the medical apparatus for imaging of the present disclosure;

FIG. 2 is a back elevational view thereof;

FIG. 3 is a top plan view thereof;

FIG. 4 is a bottom plan view thereof;

FIG. 5 is a side elevational view of the right side thereof;

FIG. 6 is a side elevational view of the left side thereof; and, FIG. 7 is a perspective view taken generally from the upper, front, right-hand side thereof.

Any portions shown in broken lines are for illustrative purposes only and form no part of the claimed design.
